UNITED STATES PATENT OFFICE

2,029,956

METHOD AND APPARATUS FOR FIRING
OIL STILLSClarence H. Thayer, Wallingford, Pa., assignor to
Sun Oil Company, Philadelphia, Pa., a corpora-
tion of New Jersey

Application August 15, 1935, Serial No. 36,334

12 Claims. (Cl. 196—110)

The present invention relates to an apparatus and method for recovering and utilizing any gases or vapors which escape or leak from the return bends or headers commonly used in tubular oil stills or heaters.

In such stills the leakage from the return bends and other connections may at times be a substantial amount of oil. This leakage not only represents a considerable loss, but also creates a considerable fire hazard. It is apparent that if this leakage of oil can be recovered and properly burned within the still, a proportionate saving in the fuel cost can be effected and the fire hazard caused by this leakage can be reduced or eliminated.

It is therefore an object of the present invention to provide a method and apparatus for recovering the vapors of any oil leaking from the return bends of oil stills and for utilizing the same as part of the fuel for heating the still.

It is a further object of this invention to provide a method and apparatus for recovering this leakage in a manner which will reduce to a minimum the danger of fire or explosion.

Other and further objects will be apparent to one skilled in the art on reading this specification and on reference to the drawing attached thereto and which forms a part thereof.

Referring now to the drawing in which the single figure is a diagrammatic representation of the apparatus for carrying out the present invention:

A designates the heating zone of a tubular oil still or heater having a series of tubes 1 arranged therein. The tubes 1 extend through the walls of the heating zone A of the still and are connected by return bends 3 in header boxes 4. Oil to be heated is admitted to the tubes through pipe 5 and leaves the still through pipe 6.

B designates the combustion zone of the tubular oil still in which fuel from burner 7 is burned, air to support combustion being introduced through air duct 8. The hot gases from combustion zone B rise through the heating zone A, passing over the tubes 1 therein and heating the oil flowing therein. These hot gases leave the still through flues 9, a portion of them flowing through flue 10, air preheater 14 and flue 15 to stack 16. The remainder of the gases from flues 9 are drawn down flue 11 by fan 12 and are reintroduced to the combustion zone B of the still through recirculation duct 13.

A portion of the gases from recirculation duct 13 pass through duct 17, having valve 33 therein, to an auxiliary combustion chamber 18, in which

gaseous or liquid fuel is burned by burner 19, a limited quantity of air being admitted, if necessary, through a controllable air inlet 20. The flue gases from auxiliary combustion chamber 18 pass through duct 21 to cooler 22 and thence through branched duct 23 to the header boxes 4, thence through branched duct 24 to combustion zone B of the stills.

Air, for supporting combustion in zone B of the still, is forced by fan 25 through cooler 22, thence through duct 26 to air preheater 14, and thence through air duct 8 to the combustion zone B of the still.

A more detailed description of the operation of that part of the apparatus which comprises the present invention is as follows:

There is considerable leakage from return bends 3, of the oil flowing through the tubes 1. The oil which leaks from return bends 3, if it is not already vaporized in the tubes 1, will be instantly vaporized in header boxes 4 as a result of the relatively high temperatures existing there, and due to the fact that the pressure in header boxes 4 is practically atmospheric. Since these vapors are highly inflammable, they not only constitute an appreciable waste, but also create a considerable fire hazard. In order to remove these vapors from the header boxes 4, a portion of the flue gases in recirculation duct 13 are led through duct 17 to auxiliary combustion chamber 18. In the operation of the tubular oil stills the relative amounts of fuel and air admitted to the combustion zone of the still may be so controlled that the flue gases issuing from the still may have a high enough free oxygen content to support combustion. If so, it is necessary that the free oxygen content of the gases in duct 17 be reduced to a point where they will no longer support combustion. This is accomplished by burning sufficient fuel in chamber 18 by the burner 19 to decrease the free oxygen content of the gases issuing from chamber 18, through duct 21, to a point where they will no longer support combustion, if necessary a controlled quantity of air may be introduced into chamber 18 through the controllable air inlet 20.

These gases then pass through the cooler 22 where they are cooled by indirect heat exchange with the air from fan 25. The cooled gases then flow through branched flue 23 to the header boxes 4. The cooled gases flowing through the header boxes reduce the temperature of the return bends, particularly the outer portion such as the plug holding members, and prevent distortion which might occur at high temperatures. In addition, since the gases from

branches duct 23 will not support combustion, the inflammable vapors of any oil leaking from the return bends 3 cannot ignite, but such inflammable vapors are mixed with the inert gases in header boxes 4, and this mixture of inert gases and inflammable vapors leave the header boxes 4 through branched duct 24 to the combustion zone B of the still. Here the inflammable vapors from header boxes 4 will mix with the air introduced by air duct 8 and be burned, thus serving as part of the fuel for heating the oil flowing in tubes 1.

Various modifications will occur to one skilled in the art. For instance, instead of taking flue gases from recirculation duct 13 and introducing them into auxiliary combustion chamber 18, flue gases may be drawn from flue 16 through duct 27, having valve 30 therein, by fan 28 and introduced into chamber 18, the valves 33 and 32 being closed. Or valves 33 and 30 may be closed and valve 32 in line 31 opened and flue gases may be taken from flue 15 through lines 31 and 27, by fan 28, and introduced into chamber 18, since the gases in flue 15 are partially cooled after passing through air preheater 14, the cooler 22 may be omitted. Instead of using any of these sources for flue gases to be introduced into chamber 18 and thence into header boxes 4, the combustion chamber 18 may be used as a flue gas generator to supply flue gases for introduction into header boxes 4, the amount of air admitted through controllable air openings 29 being so regulated that the flue gases issuing from chamber 18 will not support combustion. Or, if desired, steam or some other inert gas may be admitted to the header boxes 4 and used for removing the vapors of any oil leakage therefrom, as by closing valves 30, 32 and 33 and admitting the steam or other inert gas, through controlled inlet 20 to chamber 18 and thence through ducts 21 and 23 to the header boxes 4.

In case the oil leakage is greater than the fuel requirements of the oil still or heater, or when it is desired to shut off the fires therein, as when shutting down, part or all of the inert gas and oil vapor mixture flowing through duct 24 may be vented through valved duct 29 to the atmosphere.

What I claim and desire to protect by Letters Patent is as follows:

1. The method for removing from the header boxes of the tubular oil stills the vapors of oil escaping thereinto from the return bends of said stills, which comprises introducing an inert gas into the header boxes, and removing said inert gas with the oil vapors mixed therewith from said header boxes.

2. The method of minimizing leakage of oil from the return bends of the tubes of an oil still into the header boxes enclosing said return bends which comprises flowing through the header boxes an inert gas at a temperature substantially below the temperature in the combustion zone of the still.

3. The method of minimizing leakage of oil from the return bends of the tubes of an oil still into the header boxes enclosing said return bends which comprises circulating a portion of the flue gases from said still through the header boxes.

4. The method for recovering vapors escaping from return bends of an oil heating still and utilizing the same for fuel, which comprises mixing said vapors with an inert gas and introducing

said mixture into the combustion zone of said still.

5. The method for recovering vapors escaping from the return bends of an oil heating still and utilizing the same for fuel which comprises circulating a portion of the flue gases from said still past said return bends and introducing the gases thus circulated into the combustion zone of said still. 5

6. The method for recovering vapors escaping from the return bends of an oil heating still, which comprises mixing a portion of the flue gases from said still with an inert gas to form a non-combustion supporting mixture, passing said mixture around said return bends and then introducing said mixture into the combustion zone of said still. 10 15

7. The method of recovering and utilizing the vapors of oil leaking from the return bends of oil heating stills which comprises withdrawing a portion of the flue gases from said still and burning sufficient fuel in the gases thus withdrawn to lower the free oxygen content of the same to a point where said flue gases will no longer support combustion, then flowing said gases past 25 said return bends and then introducing said gases into the combustion zone of said still.

8. The method of recovering and utilizing the vapors of oil leaking from the return bends of oil heating stills which comprises withdrawing a portion of the flue gases from said still, burning sufficient fuel in the gases thus withdrawn to lower the free oxygen content of the same to a point where said flue gases will no longer support combustion, cooling said gases, flowing said gases past 35 said return bend and then introducing said gases into the combustion zone of said still.

9. The combination with a tubular oil still in which the tubes are connected by return bends, 40 means for introducing an inert gas into said header boxes, and means for flowing gases from said header boxes to the combustion zone of said still.

10. The combination with a tubular oil still in which the tubes are connected by return bends, 45 means for withdrawing a portion of the flue gases from said still, means for burning a controlled quantity of fuel in the gases thus withdrawn, 50 means for introducing said gases to said header boxes, and means for flowing said gases from said header boxes to the combustion zone of said still.

11. The combination with a tubular oil still in which the tubes are connected by return bends, 55 means for withdrawing a portion of the flue gases from said still, means for burning a controlled quantity of fuel in the gases thus withdrawn, means for cooling said gases, means for introducing said gases to said header boxes, and means for flowing said gases from said header boxes to the combustion zone of said still. 60

12. The combination with a tubular oil still in which the tubes are connected by return bends of 65 header boxes surrounding said return bends, means for generating non-combustion supporting flue gases, means for introducing said gases to said header boxes, and means for flowing said gases from said header boxes to the combustion 70 zone of said still.

CLARENCE H. THAYER.
